(57) **ABSTRACT**

There is provided an ink-jet printer comprising: a recording head, an electric power supply, and a controller which is configured: to determine an ink amount in which an ink is jetted by the recording head in a flushing processing; in a case that the determined ink amount is less than a first ink amount, to boost a driving voltage of the electric power supply to a target voltage value, in accordance with a predetermined first voltage boosting pattern; and in a case that the determined ink amount is not less than the first ink amount, to boost the driving voltage to the target voltage value, in accordance with a predetermined second voltage boosting pattern in which a voltage boosting time is shorter than that in the first voltage boosting pattern. Accordingly, it is possible to shorten FPOT while reducing the load on the constitutive elements of the ink-jet printer.

INK-JET PRINTER

**CROSS REFERENCE TO RELATED
APPLICATION**

The present application claims priority from Japanese Patent Application No. 2017-064560 filed on Mar. 29, 2017 the disclosure of which is incorporated herein by reference in its entirety.

BACKGROUND

Field of the Invention

The present invention relates to an ink-jet printer configured to record an image, etc., on a sheet.

Description of the Related Art

Conventionally, an attempt is made, in an information processing apparatus and a printer which are connected to each other via a communication network, to shorten FPOT (abbreviation of First Print Out Time) that is a time since a print instruction or command is input to the information processing apparatus (terminal) until a first sheet is discharged from the printer. Further, as one of the methods for shortening the FPOT, it is considered to shorten the time for a preparing processing.

The preparing processing is a processing that the printer should execute before the printer records an image on a sheet, and is exemplified, for example, by a voltage boosting processing for boosting a driving voltage to be applied to a recording head, a flushing processing for causing the recording head to jet or discharge an ink toward an ink receiver, a drive switching processing for switching a transmittance destination to which the driving force generated by a motor is transmitted, an initial conveying processing for conveying the sheet up to a position at which the sheet faces the recording head, etc.

SUMMARY

The respective processings composing the preparing processing include a processing which cannot be executed unless another processing or processings is/are ended, a processing which is executable in parallel with another processing or processings, etc. Therefore, the execution time for the preparing processing is a sum of the executing times of the respective processings which are executed in series. On the other hand, the execution time of each of the respective processings composing the preparing processing is set to be longer than a minimum required time to reduce any load on the constitutive elements or parts (for example, a motor, a gear, an electronic circuit, etc.) of the ink-jet printer (ink-jet recording apparatus). Accordingly, simply reducing the execution time of each of the respective processings composing the preparing processing would not be appropriate or suitable.

The present teaching has been made in view of the above-described situation, and an object of the present teaching is to provide an ink-jet printer capable of shortening the FPOT while reducing the load on the constitutive elements or parts of the ink-jet printer.

According to a first aspect of the present teaching, there is provided an ink-jet printer including: a motor; a conveyor configured to convey a medium; a switching mechanism configured to switch between a transmitting state in which

2

the switching mechanism transmits driving force of the motor to the conveyor and a non-transmitting state in which the switching mechanism does not transmit the driving force to the conveyor; a recording head having a plurality of nozzles and a plurality of driving elements corresponding to the plurality of nozzles, respectively; a power supply configured to output a driving voltage to be applied to the plurality of driving elements; an ink receiver; and a controller. In a case that the controller obtains an image recording instruction for instructing execution of recording of an image on the medium, the controller is configured to perform: controlling the power supply to boost the driving voltage of the power supply to a target voltage value, and controlling the recording head to perform flushing by applying the driving voltage to all of the plurality of driving elements with a timing being determined such that the ink jetted from each of the plurality of nozzles lands on the ink receiver, in parallel with, controlling the switching mechanism to switch the switching mechanism from the non-transmitting state toward the transmitting state, and controlling the conveyor to perform conveyance of the medium up to an initial position where an area, of the medium, in which the image is to be recorded first is capable of facing the recording head; after completion of the flushing and the conveyance of the medium up to the initial position, applying the driving voltage, which has been boosted to the target voltage value, selectively to the plurality of driving elements, in accordance with the image recording instruction, to perform the recording of the image on the medium; performing determination of an ink amount by which the recording head is configured to jet the ink in the flushing; in a case that the determined ink amount is less than a first ink amount, controlling the power supply to boost the driving voltage of the power supply to the target voltage value, in accordance with a first voltage boosting pattern; and in a case that the determined ink amount is not less than the first ink amount, controlling the power supply to boost the driving voltage to the target voltage value, in accordance with a second voltage boosting pattern in which a voltage boosting time is shorter than that in the first voltage boosting pattern.

In the ink-jet printer having the above-described configuration, the FPOT is affected by whichever ends later among a first processing group (for example, a voltage boosting processing and a flushing processing, to be described later on) which are executed in series and another second processing group (for example, a drive switching processing and an initial conveying processing, to be described later on) which are executed in series. Further, there is such a tendency that the execution time of the flushing processing becomes longer as the ink amount by which the recording head is allowed to jet the ink is greater. In view of this, as in the above-described configuration, provided that the execution time of the second processing group (for example, drive switching processing and the initial conveying processing) is a fixed value, the execution time of the voltage boosting processing is made to be shorter as the execution time of the flushing processing becomes longer. As a result, the difference in the completion time (finish time) between the two processing groups which are executed in parallel becomes small, thereby making it possible to suppress the increase in the FPOT.

Note that the second voltage boosting pattern is not such a pattern by which the driving voltage is boosted rapidly to such an extent that any large load is applied on an electronic circuit configured to boost the voltage of the electric power supply. If, however, the voltage boosting processing in

accordance with the second voltage boosting pattern is repeatedly executed, any small or slight load is consequently accumulated in the electronic circuit. In view of this, in a case that the execution time of the flushing is short, the first voltage boosting pattern in which the driving voltage is boosted in the relatively long voltage boosting time is used, thereby making it possible to reduce the load which would have otherwise accumulated in the electronic circuit.

According to a second aspect of the present teaching, there is provided an ink-jet printer including: a motor; a conveyor configured to convey a medium; a switching mechanism configured to switch between a transmitting state in which the switching mechanism transmits driving force of the motor to the conveyor and a non-transmitting state in which the switching mechanism does not transmit the driving force to the conveyor; a recording head having a plurality of nozzles and a plurality of driving elements corresponding to the plurality of nozzles, respectively; a power supply configured to output a driving voltage to be applied to the plurality of driving elements; an ink receiver; and a controller. The switching mechanism includes: a first gear arranged on a transmittance route via which the driving force is transmitted from the motor to the conveyor, the first gear movable between a first position and a second position; and a second gear arranged on the transmittance route. The second gear is configured to mesh with the first gear. The switching mechanism is switched to the transmitting state under a condition that the second gear is meshed with the first gear which is located at the first position. The switching mechanism is switched to the non-transmitting state under a condition that the second gear is separated and away from the first gear moved to a position different from the first position. In a case that the controller obtains an image recording instruction for instructing execution of recording of an image on the medium, the controller is configured to perform: controlling the power supply to boost the driving voltage of the power supply to a target voltage value, and controlling the recording head to perform flushing by applying the driving voltage to all of the plurality of driving elements with a timing being determined such that the ink jetted from each of the plurality of nozzles lands on the ink receiver, in parallel with, controlling the switching mechanism to switch the switching mechanism from the non-transmitting state to the transmitting state, and controlling the conveyor to perform conveyance of the medium up to an initial position where an area, of the medium, in which the image is to be recorded first is capable of facing the recording head; after completion of the flushing and the conveyance of the medium up to the initial position, applying the driving voltage, which has been boosted to the target voltage value, selectively to the plurality of driving elements, in accordance with the image recording instruction, to perform the recording of the image on the medium; performing determination of an ink amount by which the recording head is configured to jet the ink in the flushing; in a case that the determined ink amount is not less than a first ink amount, controlling the motor to perform clockwise and counter-clockwise rotations for a first number of times in a process during which the first gear is moved from the second position toward the first position; and in a case that the determined ink amount is less than the first ink amount, controlling the motor to perform the clockwise and counter-clockwise rotations for a second number of times, which is smaller than the first number of times, in the process during which the first gear is moved from the second position toward the first position.

In the ink-jet printer having the above-described configuration, the FPOT is affected by whichever ends later among a first processing group (for example, the voltage boosting processing and the flushing processing, to be described later on) which are executed in series and another second processing group (for example, the drive switching processing and the initial conveying processing, to be described later on) which are executed in series. Further, there is such a tendency that the execution time of the flushing processing becomes longer as the ink amount by which the recording head is allowed to jet the ink is greater. In view of this, as in the above-described configuration, provided that the execution time of the second processing group (for example, drive switching processing and the initial conveying processing) is a fixed value, the execution time of the voltage boosting processing is made to be shorter as the execution time of the flushing processing becomes longer. As a result, the difference in the completion time (finish time) between the two processing groups which are executed in parallel becomes small, thereby making it possible to suppress the increase in the FPOT.

Note that the rotating of the motor in the normal and reverse directions (performing normal and reverse rotations of the motor; hereinafter referred to as a "jiggling") is executed for meshing the first and second gears with each other appropriately. Further, the first and second gears are meshed with each other appropriately by the jiggling performed for the second number of times. However, in a case that an attempt is made to mesh the first and second gears with each other with the jiggling performed for a small number of times, any slight load is consequently accumulated in each of the gears. In view of this, in a case that the execution time of the flushing processing is long, it is possible to reduce the load which would have otherwise accumulated in the gears by performing the jiggling for the first number of times, which is greater than the second number of times.

BRIEF DESCRIPTION OF THE DRAWINGS

FIG. 1 is a perspective view depicting the outer appearance of a multi-function peripheral 10.

FIG. 2 is a vertical cross-sectional view schematically depicting the internal structure of a printer 11.

FIG. 3 is a plane view of a carriage 23 and guide rails 43 and 44.

FIG. 4A is a view schematically depicting the configuration of a maintenance section 70, and FIG. 4B is a view schematically depicting the configuration of an ink receiver 75.

FIGS. 5A, 5B and 5C are each a view schematically depicting the configuration of a switching mechanism 170, wherein FIG. 5A depicts a first state, FIG. 5B depicts a second state, and FIG. 5C depicts a third state of the switching mechanism 170.

FIG. 6 is a block diagram of the multi-function peripheral 10.

FIGS. 7A, 7B and 7C are each an example of a voltage boosting table, wherein FIG. 7A depicts a first voltage boosting table, FIG. 7B depicts a second voltage boosting table, and FIG. 7C depicts a third voltage boosting table.

FIG. 8 is a flow chart of an image recording processing.

FIG. 9 is a flow chart of a preparing condition determining processing.

FIG. 10 is a timing chart depicting an execution timing for a preparing processing in accordance with an embodiment.

FIG. 11 is a flow chart of a voltage boosting processing.

FIG. 12 is a view depicting the relationship among transition of driving voltage in the voltage boosting step, a set voltage value V, a stand-by time T, a sampling interval I, a number of sampling count N, and a threshold value Th.

FIGS. 13A and 13B are each a timing chart depicting an execution timing for a preparing processing in accordance with a modification of the embodiment, wherein FIG. 13A depicts a case wherein a jiggling is executed three times, and FIG. 13B depicts a case wherein the jiggling is executed five times.

DESCRIPTION OF THE EMBODIMENTS

In the following, an embodiment of the present teaching will be explained, with reference to the drawings. Note that, however, the embodiment explained below is merely an example of the present teaching; it goes without saying that it is possible to make any appropriate change(s) in the embodiment of the present teaching without departing from the gist and/or scope of the present teaching. Further, in the following explanation, advancement (movement) from a starting point to an end point of an arrow is expressed as an "orientation" and coming and going on a line connecting the starting point and the end point of the arrow is expressed as a "direction". Furthermore, in the following explanation, an up-down direction 7 is defined with a state in which a multi-function peripheral 10 is usably installed (a usable state; a state depicted in FIG. 1), as the reference; a front-rear direction 8 is defined, with a side on which an opening 13 of the multi-function peripheral 10 is provided is designated as the frontward side (front surface or front side); and a left-right direction 9 is defined as viewing the multi-function peripheral 10 from the frontward side (front surface).

<Overall Configuration of Multi-Function Peripheral 10>

As depicted in FIG. 1, the multi-function peripheral 10 is formed to have a substantially rectangular parallelepiped shape. The multi-function peripheral 10 includes a printer 11. The multi-function peripheral 10 is an example of an ink-jet printer. Further, the multi-function peripheral 10 may further include, for example, a scanner which is configured to read an original (manuscript) and to generate an image data of an image in the original; etc.

<Printer 11>

The printer 11 records an image, indicated by the image data, on a sheet 12 (see FIG. 2) by jetting (discharging) an ink onto the sheet 12. Namely, the printer 11 adopts a so-called ink-jet recording system. As depicted in FIG. 2, the printer 11 is provided with, as an example of a conveyor, feeding sections 15A and 15B, feed trays 20A and 20B, a discharge tray 21, a conveyance roller section 54, a recording section 24, a discharge roller section 55, and a platen 42.

<Feed Trays 20A and 20B, Discharge Tray 21>

The opening 13 (see FIG. 1) is formed in the front surface of the printer 11. The feed trays 20A and 20B are inserted into or removed from the printer 11 in the front-rear direction 8 through the opening 13. The feed trays 20A and 20B each support a plurality of pieces of the sheet 12 that are stacked in the feed tray 20A, 20B. The discharge tray 21 supports the sheet 12 discharged by the discharge roller section 55 via the opening 13.

<Feeding Sections 15A and 15B>

As depicted in FIG. 2, the feeding section 15A includes a feeding roller 25A, a feeding arm 26A, and a shaft 27A. The feeding roller 25A is rotatably supported by the feeding arm 26A at a front end thereof. The feeding arm 26A is pivotably supported by the shaft 27A supported by a frame of the

printer 11. The feeding arm 26A is urged toward the feeding tray 20A by a bias which is applied thereto by an elastic force of a spring, etc., or by the self-weight of the feeding arm 26A such that the feeding arm 26A is pivoted toward the feed tray 20A. The feeding section 15B includes a feeding roller 25B, a feeding arm 26B, and a shaft 27B. Since the specific construction of the feeding section 15B is common with that of the feeding section 15A, the explanation therefor will be omitted. The feeding section 15A feeds, with the feeding roller 25A, a sheet 12 supported by the feed tray 20A to a conveyance route 65. The feeding roller 25A is rotated by a driving force generated by the rotation of a feeding motor 101 (see FIG. 6) in a normal direction and transmitted to the feeding roller 25A. The feeding section 15B feeds, with the feeding roller 25B, a sheet 12 supported by the feed tray 20B to the conveyance route 65. The feeding roller 25B is rotated by a driving force generated by the rotation of the feeding motor 101 in the normal direction and transmitted to the feeding roller 25B.

<Conveyance Route 65>

The conveyance route 65 is a space which is defined by guide members 18 and 30 and guide members 19 and 31. The guide member 18 and the guide member 19 face with each other with a predetermined interval or gap intervened therebetween and the guide member 30 and the guide member 31 face with each other with a predetermined interval intervened therebetween, in the interior of the printer 11. The conveyance route 65 is a route or path which extends from rear-end portions of the feed trays 20A and 20B toward the rear side of the printer 11. Further, the conveyance route 65 makes a U-turn frontwardly while extending from the lower side to the upper side, at the rear side of the printer 11; and then the conveyance route 65 reaches the discharge tray 21 via the recording section 24.

Note that a conveyance direction 16 in which the sheet 12 is conveyed inside the conveyance route 65 is indicated by an arrow of a dot-dash chain line in FIG. 2.

<Conveyance Roller Section 54>

The conveyance roller section 54 is arranged on the upstream side from the recording section 24 in the conveyance direction 16. The conveyance roller section 54 includes a conveyance roller 60 and a pinch roller 61 which are facing each other. The conveyance roller 60 is driven by a conveyance motor 102 (see FIG. 6). The pinch roller 61 rotates following the rotation of the conveyance roller 60. The sheet 12 is conveyed in the conveyance direction 16 by being pinched between the conveyance roller 60 and the pinch roller 61. In this situation, the conveyance roller 60 is rotated in the normal direction (rotated normally or positively) by being transmitted with a driving force generated by the rotation of the conveyance motor 102 in the normal direction, and conveys the sheet 12 in the conveyance direction 16. The conveyance roller 60 rotates in a reverse direction, which is reverse to that of the normal direction of the normal rotation, by being transmitted with a driving force generated by the rotation of the conveyance motor 102 in the reverse direction.

<Discharge Roller Section 55>

The discharge roller section 55 is arranged on the downstream side from the recording section 24 in the conveyance direction 16. The discharge roller section 55 includes a discharge roller 62 and a spur 63 which are facing each other. The discharge roller 62 is driven by the conveyance motor 102. The spur 63 rotates following the rotation of the discharge roller 62. The sheet 12 is conveyed in the conveyance direction 16 by being pinched between the discharge roller 62 and the spur 63. In this situation, the

discharge roller 62 is rotated in the normal direction by being transmitted with the driving force generated by the rotation of the conveyance motor 102 in the normal direction.

<Registration Sensor 120>

As depicted in FIG. 2, the printer 11 is provided with a registration sensor 120. The registration sensor 120 is arranged upstream from the conveyance roller section 54 in the conveyance direction 16. The registration sensor 120 is an example of a sheet sensor configured to detect presence or absence of the sheet 12 at a location, within the conveyance route 65 of the sheet 12, on the upstream side from the recording head 24 in the conveyance direction 16. The registration sensor 120 outputs different detection signals, depending on whether or not the sheet 12 is present at an arrangement position. Under a condition that the sheet 12 is present at the arrangement position, the registration sensor 120 outputs a HIGH level signal to a controller 130 (to be described later on; see FIG. 6). On the other hand, under a condition that the sheet 12 is not present (is absent) at the arrangement position, the registration sensor 120 outputs a LOW level signal to controller 130.

<Rotary Encoder 121>

As depicted in FIG. 6, the printer 11 is provided with a rotary encoder 121 which is configured to generate a pulse signal depending on the rotation of the conveyance roller 60 (in other words, the rotary driving of the conveyance motor 102). The rotary encoder 121 is provided with an encoder disc and an optical sensor. The encoder disc rotates together with the rotation of the conveyance roller 60. The optical sensor reads the rotating encoder disc so as to generate a pulse signal, and outputs the generated pulse signal to the controller 130.

<Recording Section 24>

As depicted in FIG. 2, the recording section 24 is arranged between the conveyance roller section 54 and the discharge roller section 55 in the conveyance direction 16. Further, the recording section 24 is arranged to face the platen 42 in the up-down direction 7. Furthermore, the recording section 24 includes a carriage 23, a recording head 39, an encoder sensor 38A and a media sensor 122. Further, as depicted in FIG. 3, an ink tube 32 and a flexible flat cable 33 are connected to the carriage 23. An ink in an ink cartridge is supplied to the recording head 39 via the ink tube 32. The flexible flat cable 33 electrically connects the recording head 39 to a control circuit board having the controller 130 mounted thereon.

As depicted in FIG. 3, the carriage 23 is supported by guide rails 43 and 44 which are extended respectively in the left-right direction 9, at positions separated respectively in the front-rear direction 8. The carriage 23 is connected to a known belt mechanism disposed on the guide rail 44. Note that the belt mechanism is driven by a carriage motor 103 (see FIG. 6). Namely, the carriage 23, connected to the belt mechanism which circumferentially moves by being driven by the carriage motor 103, is capable of reciprocating in the left-right direction 9 in an area including a sheet facing area.

The sheet facing area means an area in a main scanning direction in which an object such as the carriage 23 may face a sheet 12 conveyed by the conveyance roller section 54 and the discharge roller section 55. In other words, the sheet facing area means an area which is included in a space located above the sheet conveyed onto the platen 42 by the conveyance roller section 54 and the discharge roller section 55 and in which the carriage 23 may pass therethrough. Further, the carriage 23 is capable of moving in the left-right direction 9 between an area located on the left side from the

sheet facing area and another area located on the right side from the sheet facing area. The left-right direction 9 is an example of the main scanning direction.

As depicted in FIG. 2, the recording head 39 is installed or mounted on the carriage 23. A plurality of nozzles 40 is formed in the lower surface of the recording head 39 (in the following description, the lower surface of the recording head 39 will be referred to as a "nozzle surface"). Further, the recording head 39 has a plurality of driving elements 10 which correspond to the plurality of nozzles 40, respectively. Namely, the recording head 39 has a plurality of nozzles and a plurality of driving elements as a plurality of sets thereof, each of the sets including one of the plurality of nozzles and one of the plurality of driving elements. In the recording head 39, each of the driving elements such as a piezoelectric element is vibrated to thereby jet or discharge an ink droplet of an ink through one of the nozzles 40. In a process during which the carriage 23 is moved, the recording head 39 jets the ink droplets toward the sheet 12 supported by the platen 42. Accordingly, an image, etc. is recorded on the sheet 12.

The driving element is an example of a jetting energy-generating element which generates, from driving voltage applied by an electric power supply 110 (see FIG. 6), an energy for causing the ink droplet to be jetted or discharged from the nozzle 40 (namely, the vibrational energy). Note that, however, the specific example of the jetting-energy generating element is not limited to the driving element, and may be, for example, a heater which generates thermal energy. Further, the heater may heat the ink by thermal energy generated from a driving voltage applied by the electrical power supply 110, and may cause an ink droplet, which is foamed by being heated, to be jetted from the nozzle. Furthermore, although the recording head 39 according to the present embodiment jets a pigment ink, the recording head 30 may jet a dye ink.

The plurality of nozzles 40 are arranged in rows in the front-rear direction 8 and the left-right direction 9, as depicted in FIGS. 2 and 4. The nozzles 40 arranged to form a row in the front-rear direction 8 (hereinafter referred to as a "nozzle row") jet ink droplets of a same color. The nozzle surface is formed with 24 nozzle rows which are arranged in the left-right direction 9. Further, every six adjacent nozzle rows, among the 24 nozzle rows, jet ink droplets of a same color ink. In the present embodiment, among the 24 nozzle rows, six nozzle rows from the right end jet ink droplets of a black ink, another six nozzle rows adjacent to the six nozzle rows jet ink droplets of a yellow ink, yet another six nozzle rows adjacent to the another six nozzle rows jet ink droplets of a cyan ink, and still yet another six nozzle rows from the left end jet ink droplets of a magenta ink. Note that, however, the combination of the number of the nozzle row and the colors of inks to be jetted are not limited to the above-described examples.

Further, an encoder strip 38B, which has a band-shape and which extends in the left-right direction 9, is arranged on the guide rail 44, as depicted in FIG. 3. The encoder sensor 38A is mounted on the lower surface of the carriage 23 at a position at which the encoder sensor 38A faces the encoder strip 38B. In a process in which the carriage 23 is moved, the encoder sensor 38A reads the encoder strip 38B to thereby generate a pulse signal, and outputs the generated pulse signal to the controller 130. The encoder sensor 38A and the encoder strip 38B construct a carriage sensor 38 (see FIG. 6).

<Media Sensor 122>

As depicted in FIG. 2, the media sensor 122 is mounted on the carriage 23 at the lower surface (surface facing the

platen 42) of the carriage 23. The media sensor 122 is provided with a light emitting section constructed of a light emitting diode, etc., and a light receiver constructed of an optical sensor, etc. The light emitting section irradiates a light at a light amount instructed by the controller 130 toward the platen 42. The light irradiated from the light emitting section is reflected by the platen 42 or a sheet 12 supported by the platen 42, and the reflected light is received by the light receiver. The media sensor 122 outputs, to the controller 130, a detection signal depending on a light receiving amount in the light receiver. For example, as the light receiving amount is greater, the media sensor 122 outputs a detection signal of higher level to the controller 130.

<Platen 42>

As depicted in FIG. 2, the platen 42 is arranged between the conveyance roller section 54 and the discharge roller section 55 in the conveyance direction 16. The platen 42 is arranged so as to face the recording section 24 in the up-down direction 7. The plane 42 supports the sheet 12, conveyed by at least one of the conveyance roller section 54 and the discharge roller section 55, from therebelow. The light reflectance of the platen 42 in the present embodiment is set to be lower than that of the sheet 12.

<Maintenance Section 70>

As depicted in FIG. 3, the printer 11 is further provided with a maintenance section 70. The maintenance section 70 is configured to perform maintenance for the recording head 39. More specifically, the maintenance section 70 executes a purge operation of removing an ink and air inside the nozzles 40, and any foreign matter or substance adhered to the nozzle surface. The ink, air, foreign matter, etc., which are removed by the maintenance section 70 are stored in a waste liquid tank 74 (see FIG. 4A). As depicted in FIG. 3, the maintenance section 70 is arranged at a location which is on the right side relative to the sheet facing area and which is below the sheet facing area. The maintenance section 70 is provided with a cap 71, a tube 72 and a pump 73, as depicted in FIG. 4A.

The cap 71 is constructed of a rubber. In a case that the carriage 23 is located at a maintenance position on the right side relative to the sheet facing area, the cap 71 is located at a position at which the cap 71 faces the recording head 39 mounted on the carriage 23. The tube 72 reaches the waste liquid tank 74 from the cap 71 and via the pump 73. The pump 73 is, for example, a tube pump of a rotary system. The pump 73 is driven by the conveyance motor 102 to thereby suck the ink, air, foreign matter, etc., inside the nozzles 40 via the cap 71 and the tube 72, and to discharge the sucked ink, air, foreign matter, etc., to the waste liquid tank 74 via the tube 72.

The cap 71 is constructed, for example, to be movable between a covering position and a separate position which are separate and away in the up-down direction 7. The cap 71 located at the covering position makes tight contact with the recording head 39 mounted on the carriage 23 which is located at the maintenance position, and covers the nozzle surface. On the other hand, the cap 71 located at the separate position is separated and away from the nozzle surface. The cap 71 is movable between the covering position and the separate position by a non-illustrated ascending/descending mechanism which is driven by the feeding motor 101. Note that, however, the specific configuration for causing the cap 71 to make contact with the recording head 39 and for separating the cap 71 from the recording head 39 is not limited to the above-described example.

As another example, it is allowable that the cap 71 is moved by a non-illustrated link mechanism which operates accompanying with the movement of the carriage 23, instead of being moved by the ascending/descending mechanism driven by the feeding motor 101. The posture of the link mechanism is changeable from a first posture in which the link mechanism holds the cap 71 at the covering position, and a second posture in which the link mechanism holds the cap 71 at the separate position. For example, the link mechanism is contacted by the carriage 23 moving rightwardly toward the maintenance position and thus the posture of the link mechanism is changed from the second posture into the first posture. On the other hand, for example, the link mechanism is contacted by the carriage 23 moving leftwardly from the maintenance position and thus the posture of the link mechanism is changed from the first posture into the second posture.

As still another example, it is allowable that the multi-function peripheral 10 is provided with an ascending/descending mechanism which moves the guide rails 43 and 44 in the up-down direction 7, instead of the mechanism which moves the cap 71. Namely, the carriage 23 at the maintenance position is ascended/descended together with the guide rails 43 and 44 which are ascended/descended by the ascending/descending mechanism. On the other hand, the cap 71 is fixed to a position at which the cap 71 faces the recording head 39 mounted on the carriage 23 which is located at the maintenance position. Further, the guide rails 43 and 44 and the carriage 23 are lowered or descended to a predetermined position by the ascending/descending mechanism, thereby allowing the nozzle surface of the recording head 39 to be covered by the cap 71. On the other hand, the guide rails 43 and 44 and the carriage 23 are lifted or ascended to another predetermined position by the ascending/descending mechanism, thereby allowing the recording head 39 and the cap 71 to be separated away from each other, and allowing the carriage 23 to be movable in the main scanning direction.

As yet another example, it is allowable that the multi-function peripheral 10 is provided with both the ascending/descending mechanism which moves the cap 71 and the ascending/descending mechanism which moves the guide rails 43 and 44. Further, it is allowable that the carriage 23 and the cap 71 are moved in directions, respectively, such that the carriage 23 and the cap 71 approach closely to each other, thereby bringing the cap 71 into a tight contact with the nozzle surface. Furthermore, it is allowable that the carriage 23 and the cap 71 are moved in directions, respectively, such that the carriage 23 and the cap 71 are separated away from each other, thereby allowing the cap 71 to be separated away from the nozzle surface. Namely, the above-described covering position and separate position are each a relative position of the cap 71 relative to the recording head 39. Further, by moving one or both of the recording head 39 and the cap 71, the relative position of the cap 71 relative to the recording head 39 may be changed. In other words, by moving the recording head 39 and the cap 71 relative to each other, the relative position of the cap 71 relative to the recording head 39 may be changed.

<Cap Sensor 123>

As depicted in FIG. 6, the printer 11 is further provided with a cap sensor 123. The cap sensor 123 outputs different detection signals, depending on whether or not the cap 71 is located at the covering position. Under a condition that the cap 71 is located at the covering position, the cap sensor 123 outputs a HIGH level signal to the controller 130. On the other hand, under a condition that the cap 71 is located at a

11

position different from the covering position, the cap sensor 123 outputs a LOW level signal to controller 130. Note that in a case that the cap 71 is moved from the covering position to the separate position, the detection signal outputted from the cap sensor 123 changes from the HIGH level signal to the LOW level signal before the cap 71 reaches the separate position.

<Ink Receiver 75>

As depicted in FIG. 3, the printer 11 is further provided with an ink receiver 75. The ink receiver 75 is arranged at a location which is on the left side relative to the sheet facing area and which is below the sheet facing area. More specifically, in a case that the carriage 23 is located on the left side relative to the sheet facing area, the ink receiver 75 is arranged at a position at which the ink receiver 75 faces the lower surface of the recording head 39 mounted on the carriage 23. Note that it is allowable that the maintenance section 70 and the ink receiver 75 are arranged on a same side in the main scanning direction, with the sheet facing area as the reference. Note that, however, the maintenance section 70 and the ink receiver 75 are arranged at positions which are separate and away from each other in the main scanning direction.

As depicted in FIG. 4B, the ink receiver 75 has a box-shape which is substantially rectangular parallelepiped and which has an opening 75A formed in the upper surface thereof. The width in the main scanning direction of the opening 75A is shorter than the width in the main scanning direction of the nozzle surface. Further, guide walls 75B and 75C each of which crosses the main scanning direction are arranged inside the ink receiver 75, at positions apart in the left-right direction 9, respectively.

The guide walls 75B and 75C are each a plate-shaped member spreading in the up-down direction 7 and the front-rear direction 8. Further, the guide walls 75B and 75C are disposed such that each of the guide walls 75B and 75C is inclined in the left-right direction 9. More specifically, the guide walls 75B and 75C are arranged inside the ink receiver 75 such that the left surface of each of the guide walls 75B and 75C faces (is oriented) in a left obliquely upward direction. Each of the guide walls 75B and 75C guides an ink droplet, which is jetted from the recording head 39, toward the interior or innermost surface (bottom surface) of the ink receiver 75. Note that, however, the number of the guide walls 75B, 75C is not limited to 2 (two).

<Driving Force Transmitting Mechanism 80>

As depicted in FIG. 6, the printer 11 is further provided with a driving force transmitting mechanism 80. The driving force transmitting mechanism 80 is configured to transmit the driving forces generated by the feeding motor 101 and the conveyance motor 102 to the feeding rollers 25A, 25B, the conveyance roller 60, the discharge roller 62, the ascending/descending mechanism for the cap 71 and the pump 73. The driving force transmitting mechanism 80 is constructed by combining all or a part of: a gear, a pulley, an endless annular belt, a planetary gear mechanism (pendulum gear mechanism), a one-way clutch, and the like. Further, the driving force transmitting mechanism 80 is provided with a switching mechanism 170 (see FIG. 5) configured to change a transmittance destination to which the driving forces generated by the feeding motor 101 and the conveyance motor 102 are transmitted.

<Switching Mechanism 170>

As depicted in FIG. 3, the switching mechanism 170 is arranged on the right side from (relative to) the sheet facing area. Further, the switching mechanism 170 is arranged at a location below the guide rail 43. Furthermore, the switching

12

mechanism 170 is arranged on a transmittance route of driving force from the feeding motor 101 and the conveyance motor 102 to reach the feeding rollers 25A and 25B, the ascending/descending mechanism for the cap 71, and the pump 73. As depicted in FIGS. 5A to 5C, the switching mechanism 170 is provided with a sliding member 171, driving gears 172 and 173, gears 174, 175, 176 and 177, a lever 178 and springs 179 and 180. The switching mechanism 170 is configured such that the state thereof is switchable to a first state, a second state and a third state. Each of the first and second states is an example of a transmitting state, and the third state is an example of a non-transmitting state.

The first state is such a state that the switching mechanism 170 transmits the driving force of the feeding motor 101 to the feeding roller 25A, but the switching mechanism 170 does not transmit the driving force of the feeding motor 101 to the feeding roller 25B and the ascending/descending mechanism for the cap 71. The second state is such a state that the switching mechanism 170 transmits the driving force of the feeding motor 101 to the feeding roller 25B, but the switching mechanism 170 does not transmit the driving force of the feeding motor 101 to the feeding roller 25A and the ascending/descending mechanism for the cap 71. The third state is such a state that the switching mechanism 170 transmits the driving force of the feeding motor 101 to the ascending/descending mechanism for the cap 71, but the switching mechanism 170 does not transmit the driving force of the feeding motor 101 to the feeding roller 25A and the feeding roller 25B. Further, each of the first state and the second state is also such a state that the switching mechanism 170 transmits the driving force of the conveyance motor 102 to the conveyance roller 60 and the discharge roller 62, but the switching mechanism 170 does not transmit the driving force of the conveyance motor 102 to the pump 73. The third state is also such a state that the switching mechanism 170 transmits the driving force of the conveyance motor 102 to all of the conveyance roller 60, the discharge roller 62, and the pump 73.

The sliding member 171 is a substantially columnar-shaped member which is supported by a supporting shaft (indicated in broken lines in FIG. 5) extending in the left-right direction 9. Further, the sliding member 171 is configured to be slidable in the left-right direction 9 along the supporting shaft. Furthermore, the sliding member 171 supports the driving gears 172 and 173 such that the driving gears 172 and 173 are rotatable independently from each other at locations, on the outer circumferential surface of the sliding member 171, which are shifted or separated from each other in the left-right direction 9. Namely, the sliding member 171 and the driving gears 172 and 173 make a sliding movement in the left-right direction 9 integrally.

The driving gear 172 is an example of a first gear which is rotated by the rotary driving force transmitted from the feeding motor 101 to the driving gear 172. The driving gear 172 meshes with one of the gears 174, 175 and 176. More specifically, in a case that the switching mechanism 170 is in the first state, the driving gear 172 meshes with the gear 174, as depicted in FIG. 5A. Further, in a case that the switching mechanism 170 is in the second state, the driving gear 172 meshes with the gear 175, as depicted in FIG. 5B. Furthermore, in a case that the switching mechanism 170 is in the third state, the driving gear 172 meshes with the gear 176, as depicted in FIG. 5C. A position at which the driving gear 172 is located, as depicted in FIG. 5A, is an example of the first position; a position at which the driving gear 172 is located, as depicted in FIG. 5B, is an example of the

second position; and a position at which the driving gear 172 is located, as depicted in FIG. 5C, is an example of the third position.

The driving gear 173 is rotated by the rotary driving force transmitted from the conveyance motor 102 to the driving gear 173. In a case that the state of the switching mechanism 170 is either one of the first state and the second state, the meshing of the driving gear 173 with the gear 177 is released, as depicted in FIGS. 5A and 5B. Further, in a case that the state of the switching mechanism 170 is the third state, the driving gear 173 meshes with the gear 177, as depicted in FIG. 5C.

The gear 174 is an example of a second gear which meshes with a gear train rotating the feeding roller 25A. Namely, the rotary driving force of the feeding motor 101 is transmitted to the feeding roller 25A by the meshing of the driving gear 172 with the gear 174. Further, the rotary driving force of the feeding motor 101 is not transmitted to the feeding roller 25A due to the release of meshing of the driving gear 172 with the gear 174.

The gear 175 is an example of a fourth gear which meshes with a gear train rotating the feeding roller 25B. Namely, the rotary driving force of the feeding motor 101 is transmitted to the feeding roller 25B by the meshing of the driving gear 172 with the gear 175. Further, the rotary driving force of the feeding motor 101 is not transmitted to the feeding roller 25B due to the release of meshing of the driving gear 172 with the gear 175.

The gear 176 is an example of a third gear which meshes with a gear train driving the ascending/descending mechanism for the cap 71. Namely, the rotary driving force of the feeding motor 101 is transmitted to the ascending/descending mechanism for the cap 71 by the meshing of the driving gear 172 with the gear 176. Further, the rotary driving force of the feeding motor 101 is not transmitted to the ascending/descending mechanism for the cap 71 due to the release of meshing of the driving gear 172 with the gear 176.

The gear 177 meshes with a gear train driving the pump 73. Namely, the rotary driving force of the conveyance motor 102 is transmitted to the pump 73 by the meshing of the driving gear 173 with the gear 177. Further, the rotary driving force of the conveyance motor 102 is not transmitted to the pump 73 due to the release of meshing of the driving gear 173 with the gear 177. On the other hand, the rotary driving force of the conveyance motor 102 is transmitted to the conveyance roller 60 and the discharge roller 62 not via the switching mechanism 170. Namely, the conveyance roller 60 and the discharge roller 62 are rotated by the rotary driving force transmitted thereto from the conveyance motor 102, regardless of the state of the switching mechanism 170.

The lever 178 is supported by the supporting shaft at a location adjacent to a right side portion of the sliding member 171. Further, the lever 178 is configured to be slidable in the left-right direction 9 along the supporting shaft. Furthermore, the lever 178 is projected upwardly. Moreover, a forward end (tip portion) of the lever 178 reaches up to a position at which the forward end is capable of contacting with the carriage 23, via an opening 43A (see FIG. 3) formed in the guide rail 43. The lever 178 is configured to be slidable in the left-right direction 9 by being contacted by the carriage 23 and by being separated from the carriage 23. Further, the switching mechanism 170 is provided with a plurality of locking sections configured to lock the lever 178. Accordingly, the lever 178, in a state of being locked by a locking section among the plurality of locking sections and then being separated from the carriage 23 at a

certain location, may remain at the certain location even after the lever 178 has been separated away from the carriage 23.

The springs 179 and 180 are supported by the supporting shaft. The spring 179 makes contact with the frame of the printer 11 at one end (left end) of the spring 179, and the spring 179 makes contact with the left end surface of the sliding member 171 at the other end (right end) of the spring 179. Namely, the spring 179 urges the sliding member 171 and the lever 178 contacting the sliding member 171 rightwardly. The spring 180 makes contact with the frame of the printer 11 at one end (right end) of the spring 180, and the spring 180 makes contact with the right end surface of the lever 178 at the other end (left end) of the spring 180. Namely, the spring 180 urges the lever 178 and the sliding member 171 contacting the lever 178 leftwardly. Further, the urging force of the spring 180 is greater than the urging force of the spring 179.

In a case that the lever 178 is locked by a first locking section included in the plurality of locking sections, the switching mechanism 170 is in the first state. Then, the lever 178, pushed or pressed by the carriage 23 moving rightwardly, moves rightwardly against the urging force of the spring 180, and is locked by a second locking section located on the right side with respect to the first locking section. With this, the sliding member 171 moves rightwardly, by the urging force of the spring 179, following the movement of the lever 178. As a result, the state of the switching mechanism 170 is changed from the first state depicted in FIG. 5A to the second state depicted in FIG. 5B. Namely, the lever 178 is contacted by the carriage 23 which is moving rightwardly toward the maintenance position to thereby switch the state of the switching mechanism 170 from the first state into the second state.

Further, the lever 178, pressed by the carriage 23 moving rightwardly up to the maintenance position, moves rightwardly against the urging force of the spring 180, and is locked by a third locking section located farther on the right side with respect to the second locking section. With this, the sliding member 171 moves rightwardly, by the urging force of the spring 179, following the movement of the lever 178. As a result, the state of the switching mechanism 170 is changed from the first state depicted in FIG. 5A or the second state depicted in FIG. 5B to the third state depicted in FIG. 5C. Namely, the lever 178 is contacted by the carriage 23 which is moving rightwardly toward the maintenance position to thereby switch the state of the switching mechanism 170 into the third state.

Furthermore, the lever 178, pressed by the carriage 23 moving farther rightwardly from the maintenance position and then separated away from the carriage 23 moving leftwardly, is released from the locking by the third locking section. With this, the sliding member 171 and the lever 178 are moved leftwardly by the urging force of the spring 180. Then, the lever 178 is locked by the first locking section. As a result, the state of the switching mechanism 170 is changed from the third state depicted in FIG. 5C to the first state depicted in FIG. 5A. Namely, the lever 178 is separated from the carriage 23 which is moving leftwardly from the maintenance position to thereby switch the state of the switching mechanism 170 from the third state into the first state.

Namely, the state of the switching mechanism 170 is switched by the contact and separation of the carriage 23 with respect to the lever 178. In other words, the transmission destinations of the driving forces of the feeding motor 101 and the conveyance motor 102 are switched by the carriage 23. In a state that the lever 178 is locked by the third

locking section, the lever 178 holds the driving gear 172 at the second position against urging forces of the springs 179 and 180. In a state in which the lever 178 is not locked by the third locking section, the lever 178 allows the driving gear 172 to move. Note that the state of the switching mechanism 170 according to the present embodiment is not switched directly from the third state to the second state; rather, the state of the switching mechanism 170 is required to be switched from the third state to the first state, then further switched from the first state to the second state, as described above.

<Electric Power Supply 110>

The multi-function peripheral 10 has the electric power supply 110, as depicted in FIG. 6. The electric power supply 110 has a variety of kinds of electronic circuits configured to supply the electric power, supplied thereto from an external power supply via a power plug, to the respective constituent components, parts, etc., of the multi-function peripheral 10. More specifically, the electric power supply 110 outputs the electric power obtained from the external power supply as a driving voltage (for example, 24V) to the respective motors 101 to 103 and the recording head 39, and outputs the electric power as a controlling voltage (for example, 5V) to the controller 130.

Further, the electric power supply 110 is capable of being switched (switchable) between a driving state and a sleeping state, based on a power signal outputted from the controller 130. More specifically, the controller 130 outputs a HIGH level power signal (for example, 5V) to thereby switch the electric power supply 110 from the sleeping state to the driving state. On the other hand, the controller 130 outputs a LOW level power signal (for example, 0V) to thereby switch the electric power supply 110 from the driving state to the sleeping state.

The term “driving state” means a state in which the driving voltage is outputted to the motors 101 to 103 and to the recording head 39. In other words, the driving state means a state in which the motors 101 to 103 and the recording head 39 are each in an operable state or an active state. The term “sleeping state” means a state in which the driving voltage is not outputted to the motors 101 to 103 and to the recording head 39. In other words, the sleeping state means a state in which the motors 101 to 103 and the recording head 39 are each in an inoperative state or an inactive state. Although not depicted in the drawings, the electric power supply 110 outputs the controlling voltage to the controller 130 and a communicating section 50 (see FIG. 6), regardless of whether or not the electric power supply 110 is in the driving state or in the sleeping state.

<Controller 130>

As depicted in FIG. 6, the controller 130 is provided with a CPU 131, a ROM 132, a RAM 133, an EEPROM 134 and an ASIC 135 which are connected to one another by an internal bus 137. The ROM 132 stores various programs which are executed by the CPU 131 to thereby control a variety of kinds of operations. The RAM 133 is used as a storage area for temporarily storing a data and/or signal, etc., to be used when the CPU 131 executes the program(s), or as a working area for data processing. The EEPROM 134 stores setting information which should be retained even after the power supply of the multi-function peripheral 10 is switched off.

The feeding motor 101, the conveyance motor 102 and the carriage motor 103 are connected to the ASIC 135. The ASIC 135 generates a driving signal for rotating each of the motors, and outputs the generated driving signal to each of the motors. Each of the motors is driven to rotate in the

normal direction or in the reverse direction, in accordance with the driving signal from the ASIC 135. Further, the controller 130 applies the driving voltage of the electric power supply 110 to the driving elements, via a non-illustrated driver IC of the recording head 39, to thereby cause the ink droplets to be jetted or discharged from the nozzles 40 corresponding to the driving elements, respectively.

Further, the communicating section 50 is connected to the ASIC 135. The communicating section 50 is a communicating interface capable of communicating with an information processing apparatus 51. Namely, the controller 130 transmits or sends a variety of kinds of information to the information processing apparatus 51 via the communicating section 50, and receives or accepts a variety of kinds of information from the information processing apparatus 51 via the communicating section 50. The communicating section 50 may be, for example, configured to transmit and receive a radio signal by a communication protocol in accordance with Wi-Fi (trade name by Wi-Fi Alliance), or may be an interface to which a LAN cable or a USB cable is connected. Note that in FIG. 6, the information processing apparatus 51 is surrounded by a frame drawn with a broken line so as to distinguish the information processing apparatus 51 from the constituents of the multi-function peripheral 10.

Further, the registration sensor 120, the rotary encoder 121, the carriage sensor 38, the media sensor 122 and the cap sensor 123 are connected to the ASIC 135. The controller 130 detects the position of the sheet 12 based on the detection signal outputted from the registration sensor 120 and the pulse signal outputted from the rotary encoder 121. Further, the controller 130 detects the position of the carriage 23 based on the pulse signal outputted from the carriage sensor 38. Furthermore, the controller 130 detects the position of the cap 71 based on the detection signal outputted from the cap sensor 123.

Moreover, the controller 130 detects the sheet 12 conveyed by the conveyance roller section 54 and the discharge roller section 55 based on the detection signal outputted from the media sensor 122. More specifically, the controller 130 compares an amount of change (change amount) in signal level between detection signals, which are temporally adjacent, with a predetermined threshold value. Further, in response to that the change amount in the signal level becomes to be not less than the threshold value, the controller 130 detects that the forward end or a tip end of the sheet 12 has reached a position at which the forward end faces the media sensor 122 in the up-down direction 7.

Further, the EEPROM 134 stores time information indicating a time at which the ink has been jetted (discharged) from the nozzles 40 immediately before (hereinafter referred to as an “immediately before-jetting time”). The immediately before-jetting time is, for example, a time at which a flushing processing (to be described later on) has been executed immediately before, or a time at which a recording processing (to be described later on) has been executed immediately before. The controller 130 obtains the time information from a system clock (not depicted in the drawings) at a time at which the ink is jetted (discharged), and causes the EEPROM 134 to store the obtained time information. Further, in response to the situation that the time information has already been stored in the EEPROM 134, the controller 130 overwrites the time information already stored in the EEPROM 134 with new time information.

Further, the EEPROM 134 stores a voltage boosting table, as depicted in FIGS. 7A to 7C. The voltage boosting table is

a table retaining (holding) information for boosting the driving voltage of the electric power supply 110 such that the driving voltage has a target voltage value (for example, 24V), in step S41 (to be described later on). FIG. 7A depicts a first voltage boosting table indicating a first voltage boosting pattern, FIG. 7B depicts a second voltage boosting table indicating a second voltage boosting pattern, and FIG. 7C depicts a third voltage boosting table indicating a third voltage boosting pattern. The specific of the voltage boosting table will be described later on. The voltage boosting tables are stored in the EEPROM 134 in a process during which the multi-function peripheral 10 is manufactured. The voltage boosting tables may be stored in the ROM 132, instead of being stored in the EEPROM 134.

<Image Recording Processing>

Next, an explanation will be given about an image recording processing of the present embodiment, with reference to FIGS. 8 to 11. Note that at a time of starting the image recording processing, it is assumed that the carriage 23 is located at the maintenance position, the cap 71 is located at the covering position, and the switching mechanism 170 is in the third state. The respective processing to be described below may be executed such that the CPU 131 reads out the program stored in the ROM 132 and executes the read program, or may be executed by a hardware circuit mounted on the controller 130. Note that the order of execution of the respective processings may be appropriately changed, without departing from the gist and/or scope of the present teaching. Note that in the following explanation, Step S11 is described simply as "S11", in some cases.

At first, the controller 130 of the multi-function peripheral 10 stands by to execute the processing including and after step S12, until the controller 130 obtains (receives) an image recording instruction (S11: NO). The image recording instruction is an instruction for instructing execution of recording of an image on the sheet 12. Although the method or manner for obtaining (receiving) the image recording instruction is not particularly limited or restricted, it is allowable, for example, that the controller 130 receives the image recording instruction from the image processing apparatus 51 via the communicating section 50, or obtains (receives), from the user via a non-illustrated operation panel, an image recording instruction (a so-called copying instruction).

Next, in response to the obtainment (receipt) of the image recording instruction (S11: YES), the controller 130 executes a preparing condition determining processing (S12). The preparing condition determining processing is a processing for determining an execution condition of a preparing processing which will be described later on. The execution condition of the preparing processing includes, for example, a FLS shot count, a CR velocity, a FLS execution count and a voltage boosting pattern. The preparing condition determining condition will be explained in detail with reference to FIG. 9.

The FLS shot count is the total of ink droplets to be discharged (jetted) from each of the nozzles 40 in a FLS processing (to be described later on). Namely, the FLS shot count is an example of an ink amount of the ink to be discharged from the nozzle 40 before the recording processing. The CR velocity is the maximum value of the moving velocity of the carriage 23 in the FLS processing (in other words, a second moving processing). The FLS execution count is a number (number of times) in which the carriage 23 passes a position at which the carriage 23 faces (is opposite to) the ink receiver 75 in the FLS processing (in other words, a number of a FLS step which will be described

later on). The voltage boosting pattern is a manner by which the driving voltage is boosted, and corresponds to the voltage boosting tables as depicted in FIGS. 7A to 7C.

<Preparing Condition Determining Processing>

At first, the controller 130 obtains time information indicating the current time from the system clock. Then, the controller 130 calculates the difference between the current time and the immediately before-jetting time indicated by the time information stored in the EEPROM 134, as an elapsed time T since the ink has been discharged immediately before and until the preceding command is received. Then, the controller 130 compares the elapsed time T with a threshold time T_{th1} and a threshold time T_{th2} (S21, S22). The threshold time T_{th1} and the threshold time T_{th2} are values previously stored in the EEPROM 134, and satisfy the relationship: Threshold time $T_{th1} <$ Threshold time T_{th2} .

Under a condition that the elapsed time T is less than the threshold time T_{th1} (S21: YES), the controller 130 determines the FLS shot count to be 50 shots (S23). Further, under a condition that the elapsed time T is not less than the threshold time T_{th1} (S21: NO) and is less than the threshold time value T_{th2} (S22: YES), the controller 130 determines the FLS shot count to be 100 shots (S24). Furthermore, under a condition that the elapsed time T is not less than the threshold time value T_{th2} (S22: NO), the controller 130 determines the FLS shot count to be 500 shots (S25). Namely, the FLS shot count becomes great in a case that the elapsed time T is long. A FLS shot count between the 50 to 100 shots (for example, 75 shots) is an example of a first ink amount; the FLS shot count between the 100 to 500 shots (for example, 250 shots) is an example of a second ink amount. The processings of steps S21 to S25 are an example of a determining processing.

Next, under a condition that the FLS shot count has been determined to be 50 shots, the controller 130 determines the CR velocity to be 60 ips, determines the FLS execution count to be one time (once), and determines the voltage boosting pattern to be the first voltage boosting pattern (S26, S29). On the other hand, under a condition that the FLS shot count has been determined to be 100 shots, the controller 130 determines the CR velocity to be 4 ips, determines the FLS execution count to be one time, and determines the voltage boosting pattern to be the second voltage boosting pattern (S27, S30). Further, under a condition that the FLS shot count has been determined to be 500 shots, the controller 130 determines the CR velocity to be 4 ips, determines the FLS number of times to be three times, and determines the voltage boosting pattern to be the third voltage boosting pattern (S28, S31). Note that in each of steps S29 to S31, the controller 130 reads out the voltage boosting table indicating the determined voltage boosting pattern from the EEPROM 134.

Note that it is needless to say that the values indicated in steps S23 to S28 are each an example, and that the present teaching is not limited to or restricted by these values. In the following, the preparing processing executed in accordance with the executing condition determined in S23, S26 and S29 is described as a "first pattern"; the preparing processing executed in accordance with the executing condition determined in S24, S27 and S30 is described as a "second pattern"; and the preparing processing executed in accordance with the executing condition determined in S25, S28 and S31 is described as a "third pattern", in some cases.

Next, returning to FIG. 8, the controller 130 executes a preparing processing (S13), in accordance with the execution condition determined in the preparing condition determining processing. The preparing processing is a processing

for allowing the printer 11 to be in a state that the recording processing can be executed. The phrase that the “state that the recording processing can be executed” can be rephrased, for example, as a state that an image can be recorded with a quality of not less than a predetermined level. The preparing processing includes, for example, a voltage boosting processing (S41), a first moving processing (S42), a drive switching processing (S43), a FLS (flushing) processing (S44), a second moving processing (S45), a feeding processing (S46) and a positioning processing (initial setting processing, cue-feeding processing) (S47), as depicted in FIG. 10.

The voltage boosting processing (S41) is a processing for boosting the driving voltage of the electric power supply 110 to a target voltage value in accordance with the voltage boosting table which has been read out in step S29, S30 or S31. The details of the processing of step S41 will be described later on, with reference to FIGS. 11 and 12.

The first moving processing (S42) is a processing for moving the carriage 23, which has been separated away from the cap 71, to a flushing position located on the left side with respect to the ink receiver 75. Namely, the controller 130 causes the carriage 23 at the maintenance position to move rightwardly, and then to move leftwardly until the carriage 23 reaches the flushing position. Further, in order to suppress any destruction of the meniscus of the ink formed in the nozzles 40 of the recording head 39, it is allowable that the controller 130 causes the carriage 23 to move leftwardly at a low speed or velocity at the time at which step S42 is started, and then the controller 130 executes the processing of step S42.

The drive switching processing (S43) includes a processing for moving the cap 71 from the covering position to the separate position, and a processing for switching the state of the switching mechanism 170 from the third state to the first state. Namely, the controller 130 rotates the feeding motor 101 just by a predetermined rotational amount. Then, by allowing the rotary driving force of the feeding motor 101 to be transmitted to the ascending/descending mechanism (for the cap 71) via the switching mechanism 170 in the third state, the cap 71 is moved from the covering position to the separate position.

Further, by the movement of the carriage 23 rightwardly from the maintenance position in the first moving processing, the locking of the lever 178 by the third locking section is released (namely, the state of the lever 178 is switched from the holding state into the allowing state). With this, the sliding member 171, the driving gears 172 and 173 and the lever 178 are moved leftwardly by the urging force of the spring 180. Namely, the driving gear 172 is separated away from the gear 176, climbs over (passes over) the gear 175, and meshes with the gear 174. Further, the driving gear 173 is separated away from the gear 177. Namely, the state of the drive switching mechanism 170 is switched from the non-transmitting state into the transmitting state.

Then, the controller 130 causes both of the feeding motor 101 and the conveyance motor 102 to perform the normal and reverse rotations (hereinafter referred to as a “jiggling”), in a process during which the driving gears 172 and 173 are moved leftwardly. The jiggling is, for example, an operation for causing the feeding motor 101 and the conveyance motor 102 to perform the normal rotation or the reverse rotation just by a predetermined rotational amount, and then causing the feeding motor 101 and the conveyance motor 102 to perform the reverse rotation or the normal rotation just by the predetermined rotational amount. The rotation amounts of the feeding motor 101 and the conveyance motor 102 are,

for example, angles required for rotating the gears 172 and 173, respectively, each by not less than $\frac{1}{2}$ of the width of a tooth in the circumferential direction thereof (by not less than $\frac{1}{2}$ of the circumferential thickness of the tooth thereof) 5 (more preferably, by not less than the width of the tooth in the circumferential direction thereof).

The controller 130 executes the jiggling maximally five times with a predetermined interval, in response, for example, to the starting of the leftward movement of the carriage 23 in the first moving processing. With this, since the bearing stress between the driving gear 172 and the gear 176 and the bearing stress between the driving gear 173 and the gear 177 are released, the meshings among the respective gears can be released smoothly. Further, the driving gear 172 10 can smoothly climb (pass) over the gear 175, and can mesh smoothly with the gear 174.

Note that as depicted in FIG. 10, the controller 130 executes the processings of steps S41 to S43 in parallel. More specifically, the controller 130 starts the processing of step S41 and the processing of step S43 at the same time at 15 a timing at which the controller 130 receives the image recording instruction. Further, the controller 130 starts the processing of step S42 at a timing at which the detection signal from the cap sensor 123 is changed from the HIGH level signal to the LOW level signal. Namely, the controller 130 starts the processing of step S42 after starting the steps S41 and S43.

The FLS processing (S44) is an example of a flushing processing for causing the recording head 39 to jet (discharge) the ink toward the ink receiver 75, in accordance with the executing condition determined in the preparing condition determining processing (namely, the FLS shot count, the CR velocity and the FLS execution count). Namely, in a process during which the controller 130 causes the carriage 23 to move in the CR velocity in step S44, the controller 130 repeats the FLS step, for applying the driving voltage of the electric power supply 110 to the driving elements, in a number of times corresponding to the FLS execution count, thereby causing the recording head 39 to jet 30 the FLS shot count of the ink.

At first, as a first FLS step, the controller 130 causes the carriage 23 to move rightwardly from the flushing position, and the controller 130 applies the driving voltage to each of the driving elements which corresponds to one of the nozzles 40, at discharge timings predetermined for the nozzles 40, respectively, thereby causing the ink to be discharged from all the nozzles 40. Note that during the period in which the FLS step is being executed, the carriage 23 is accelerated from a stopped state up to the CR velocity, and moves at a constant velocity at the CR velocity. Namely, the CR velocity determined in the preparing condition determining processing indicates the maximum velocity or the target velocity of the carriage 23 during the FLS step.

An ink droplet jetting timing at which the ink droplets are 55 jetted in the FLS processing is previously determined such that the ink droplets are allowed to land on the guide walls 75B and 75C. The jetting timing for each of the nozzles 40 is specified, for example, based the encoder value of the carriage sensor 38. In the present embodiment, at an initial 60 timing, ink droplets are jetted from nozzle arrays on the right end and configured to jet the black ink and from nozzle arrays which are adjacent to the nozzle arrays, on the right end and configured to jet the black ink, and which are configured to jet the yellow ink; and then at a next timing, 65 ink droplets are jetted from two groups of nozzle arrays located to be immediate left of the nozzle arrays from which the ink droplets of the black ink and the yellow inks have

been jetted at the first timing. Namely, the controller 130 causes the ink droplets from each of the nozzles 40 in the nozzle arrangement order in the main scanning direction (namely, in an order from right to left).

Further, in a case that the FLS execution count=1 time (once), the ink droplets of which number is the FLS shot count are jetted from each of the nozzles 40 in one time of the FLS step. On the other hand, in a case that the FLS execution count=3 times (thrice), the ink droplets of which number is $\frac{1}{3}$ the FLS shot count are jetted from each of the nozzles 40 in one time of the FLS step. More specifically, the controller 130 causes each of the nozzles 40 to jet the ink in an amount corresponding to "FLS shot count/FLS execution count). Namely, in a case that the controller 130 executes a plurality of FLS steps in step S44, the controller 130 causes each of the nozzles 40 to jet the ink droplets, of which number is the FLS shot count, while distributing the FLS shot count among the plurality of FLS steps.

Next, in the case that the FLS execution count=3 times, the controller 130 causes all the nozzles 40 to jet the ink in the first FLS step, then the controller 130 causes the carriage 23 to stop at a reversing position located on the right side with respect to the ink receiver 75. Then, as a second FLS step, the controller 130 causes the carriage 23 to move leftwardly from the reversing position, and the controller 130 causes ink to be jetted from each of the nozzles 40, at discharge timings predetermined for the nozzles 40, respectively. Namely, the second FLS step is different from the first FLS step in the moving direction (leftward) of the carriage 23 and in the order in which the controller 130 causes the ink to be jetted from each of the nozzles 40 (namely, in an order from left to right).

Further, in response to the completion of the second FLS step, the controller 130 executes, as a third FLS step, a similar processing to that of the first FLS step. Namely, regardless of the FLS execution count determined in the preparing condition determining processing, the controller 130 causes the carriage 23 to move, in a last FLS step, in a direction approaching closely to the sheet facing area (namely, rightward).

Note that before the controller 130 executes the first FLS processing, the controller 130 may further execute a non-jetting flushing processing. The term "non-jetting flushing processing" means a processing for vibrating the driving elements to such an extent that any ink is not jetted from the nozzles 40. The non-jetting flushing processing may be executed at any timing after the completion of the voltage boosting processing. The execution time of the non-jetting flushing may be made longer as the elapsed time T is longer. With this, the ink droplets are allowed to be easily jetted from the nozzles 40 in the flushing processing.

The second moving processing (S45) is a processing for moving the carriage 23 rightwardly toward a detection position. Namely, the controller 130 drives the carriage motor 103 to thereby cause the carriage 23 rightwardly up to the detection position. The term "detection position" means a position which is located at the sheet facing area and at which the carriage 23 is capable of facing a sheet 12 of each of all the sizes (for example, A4, B4, L-size, etc.) supported by the feed trays 20A and 20B. In a case that the sheet 12 is supported by the feed tray 20A or 20B in a state that the center in the main scanning direction of the sheet 12 is positioned with respect to the feed tray 20A or 20B, the detection position may be located at the center in the main scanning direction of the sheet facing area.

Namely, the second moving processing in the case that the FLS execution count=1 time is a processing for moving the

carriage 23 which is being moved rightwardly in the FLS processing to move up to the detection position without causing the carriage 23 to stop after the completion of the FLS processing. On the other hand, the second moving processing in the case that the FLS execution count=3 times is a processing for moving the carriage 23 which is being moved rightwardly in the third FLS step to move up to the detection position without causing the carriage 23 to stop after the completion of the third FLS step. Further, in the 10 second moving processing in the case that the CR velocity in the FLS processing is 4 ips, the controller 130 may accelerate the carriage 23 to 60 ips after completion of the FLS processing.

The feeding processing (S46) is a processing for causing 15 the feeding section 15A to feed a sheet 12, supported by the feed tray 20A, up to a position at which the sheet 12 reaches the conveyance roller section 54. This feeding processing is executed in a case that the image recording instruction indicates the feed tray 20A as the feeding source from where the sheet 12 is fed. The controller 130 causes the feeding motor 101 to rotate normally, and causes the feeding motor 101 to further rotate normally just by a predetermined rotation amount after the detection signal of the registration sensor 120 is changed from the LOW level signal to the HIGH level signal. Further, by the transmittance of the rotary driving force of the feeding motor 101 to the feeding roller 25A via the switching mechanism 170 in the first state, the sheet 12 supported by the feed tray 20A is fed to the conveyance route 65.

The initial setting processing (cue-feeding processing) (S47) is a processing for causing the conveyance roller section 54 and the discharge roller section 55 to convey, in the conveyance direction 16, the sheet 12, which has been conveyed by the feeding processing and has reached the 35 conveyance roller section 54, up to a facing position at which an area, of the sheet 12, in which an image is to be recorded first (hereinafter referred also to as a "recording area" or "initial recording area" in some cases) may face the recording head 39. The initial recording area on the sheet 12 40 is indicated in the image recording instruction. The controller 130 causes the conveyance motor 102 to rotate normally to thereby cause the conveyance roller section 54 and the discharge roller section 55 to convey the sheet 12, which has reached the conveyance roller section 54, until the initial 45 recording area indicated by the image recording instruction faces the recording head 39. Further, the controller 130 uses the media sensor 122 to detect the forward end of the sheet 12 during the process in which the initial setting processing is being executed. The processings in steps S46 and S47 are 50 example of the initial conveying processing.

Note that the processings S44 to S47 cannot be started unless at least a portion of the processings S41 to S43 has been already completed. More specifically, the FLS processing cannot be started until the first moving processing has 55 been already completed, but can be started even if the voltage boosting processing and the drive switching processing have not been completed yet. Further, the second moving processing is started concurrently with or after the execution of the FLS processing. Furthermore, the feeding 60 processing cannot be started unless the drive switching processing has been already completed, but can be started even if the voltage boosting processing and the first moving processing have not been completed yet. Moreover, the initial setting processing cannot be started unless the feeding 65 processing has been already completed.

Namely, in response to the completion of the first moving processing, the controller 130 starts the FLS processing.

Note that as in the first and second patterns depicted in FIG. 10, the controller 130 may start the FLS processing after the completion of the voltage boosting processing. Alternatively, as in the third pattern depicted in FIG. 10, the controller 130 may start the FLS processing while executing the third voltage boosting step of the voltage boosting processing. Then, the controller 130 starts the second moving processing concurrently with the FLS processing or with the third FLS step. Further, in response to the completion of the drive switching processing, the controller 130 starts the feeding processing. Then, in response to the completion of the feeding processing, the controller 130 starts the initial setting processing.

Further, although not depicted in the drawings, in a case that the image recording instruction indicates the feed tray 20B as the feeding source from where the sheet 12 is fed and in response to the completion of the FLS processing, the controller 130 switches the state of the switching mechanism 170 from the first state to the second state. Namely, the controller 130 causes the carriage 23 which is being moved in the second moving processing to further move rightwardly, and causes the lever 178 which has been locked by the first locking section to be locked by the second locking section. Further, in response to the switching of the switching mechanism 170 into the second state, the controller 130 causes the carriage 23 to move leftwardly toward the detection position. Then, in response to the switching of the switching mechanism 170 into the second state, the controller 130 starts the feeding processing for feeding the sheet 12 supported by the feed tray 20B.

Next, in response to the completion of all the processings included in the preparing processing, the controller 130 executes the recording processing in accordance with the received image recording instruction (S14 to S17). In other words, in response to the detection of the sheet 12 by the controller 130 via the media sensor 112 during the initial setting processing and in response to the completion of the initial setting processing by the controller 130, the controller 130 executes the recording processing. The recording processing includes, for example, a jetting processing (S14) and a conveying processing (S16) which are executed alternately, and a discharging processing (S17). The jetting processing is a processing for causing the recording head 39 to jet ink droplets selectively, in accordance with the image recording instruction, with respect to the recording area of the sheet 12 which is made to face the recording head 39. The conveying processing is a processing for causing the conveyance roller section 54 and the discharge roller section 55 to convey the sheet 12 just by an amount corresponding to a predetermined conveyance width along the conveyance direction 16. The discharging processing is a processing for causing the discharge roller section 55 to discharge the sheet 12, having an image recorded thereon, to the discharge tray 21.

Namely, the controller 130 moves the carriage 23 from one end to the other end of the sheet facing area, and applies the driving voltage, boosted to the target voltage value, selectively to the driving elements at a timing indicated by the image recording instruction (S14). Next, under a condition that there is an image to be recorded on a next recording area (S15: NO), the controller 130 causes the conveyance roller section 54 and the discharge roller section 55 to convey the sheet 12 up to a position at which the next recording area faces the recording head 39 (S16). Until the controller 130 records image(s) on all the recording areas, the controller 130 executes the jetting processing and the conveying processing repeatedly. Next, under a condition

that the image(s) have been recorded on all the recording areas (S15: YES), the controller 130 causes the discharge roller section 55 to discharge the sheet 12 to the discharge tray 21 (S17).

5 Although not depicted in the drawings, under a condition that a predetermined time has elapsed since the completion of the recording processing (S14 to S17), the controller 130 moves the carriage 23 to the maintenance position, changes the state of the switching mechanism 170 into the third state, 10 and moves the cap 71 to the covering position. Further, under a condition that a predetermined time has elapsed since the movement of the cap 71 to the covering position, the controller 130 switches the state of the electric power supply 110 from the driving state to the sleeping state.

15 <Voltage Boosting Processing>

Next, the voltage boosting processing of step S41 will be explained in details with reference to FIGS. 11 and 12. The voltage boosting processing is a processing for boosting (raising) the driving voltage of the electric power supply 110 20 to (have) a target voltage value by repeating a plurality of voltage boosting steps. The plurality of voltage boosting steps as a whole is a processing for boosting the driving voltage of the electric power supply 110 to (have) a set voltage value V. By the execution of the voltage boosting 25 processing, the electric power supply 110 retains the driving voltage, which is to be applied to the driving elements so as to cause the ink to be jetted from the nozzles 40, in a non-illustrated condenser (capacitor), etc. The following explanation will be made regarding, as an example, a 30 voltage boosting processing in accordance with the second voltage boosting table depicted in FIG. 7B. Note that the driving voltage at the time of starting of the voltage boosting processing is 0 (zero) volt.

Each of records, included in the voltage boosting table, 35 corresponds to one of the plurality of voltage boosting steps. The content of the processing in each of the voltage boosting steps is, for example, specified by the set voltage value V, a stand-by time T, a sampling interval I, a number of sampling 40 count N, and a threshold value Th. The set voltage value V is a target value for the driving voltage which is to be boosted in each of the plurality of voltage boosting steps. The stand-by time T is a predetermined time which is considered as necessary for the driving voltage to reach the set voltage value V. The sampling interval I is an obtaining 45 interval at which a present (current) value of the driving voltage is (to be) obtained. The number of sampling count N is a number of times for obtaining the present value of the driving voltage. The threshold value Th is a value which is (to be) compared with an average voltage value (to be 50 described later on) so as to determine whether or not a certain voltage boosting step (among the plurality of voltage boosting steps) is completed normally. The set voltage value V is a value not more than the target voltage value, and the threshold value Th is a value less than a certain set voltage 55 value V corresponding to the certain voltage boosting step.

In the following, among the plurality of voltage boosting steps, a voltage boosting step indicated by a record including a variable $i=1$ is referred to as a “first voltage boosting step”, a voltage boosting step indicated by a record including a variable $i=2$ is referred to as a “second voltage boosting step”, and a voltage boosting step indicated by a record including a variable $i=3$ is referred to as a “third voltage boosting step”. Namely, the controller 130 executes the first 60 voltage boosting step, the second voltage boosting step and the third voltage boosting step in this order in the voltage boosting processing. Further, the set voltage value V (=22V) in the second voltage boosting step is higher than the set 65 value V in the first voltage boosting step.

voltage value V (=14V) in the first voltage boosting step. Furthermore, the set voltage value V (=24V) in the third voltage boosting step is higher than the set voltage value V (=22V) in the second voltage boosting step.

At first, the controller 130 substitutes an initial value (=1) for the variable i (S51). Next, the controller 130 outputs a voltage boosting signal Si , instructing the boosting of the driving voltage up to a set voltage value Vi (=14V) corresponding to the variable i , to the electric power supply 110 (S52). Namely, in the first voltage boosting step in FIG. 7B, the driving voltage of the electric power supply 110 is boosted from 0V to 14V. In the following, the difference between the driving voltage (=0V) at the time of starting of a certain voltage boosting step (in this case, the first voltage boosting step) and the set voltage value of the certain (first) voltage boosting step (=14V) is referred to as a "voltage boosting width". The processing in step S52 is an example of an instructing processing.

The voltage boosting signal Si is, for example, a pulse signal indicating a waveform of the driving voltage which is to be supplied to a non-illustrated regulator circuit in the electric power supply 110. The voltage boosting speed is controlled by a ratio of a HIGH level signal in the voltage boosting signal Si (hereinafter referred to as a "duty ratio"). Namely, in a case that the stand-by time T is same, as the voltage boosting width is greater, the voltage boosting signal Si is outputted with a greater duty ratio. Alternatively, in a case that the voltage boosting width is same, as the stand-by time T is shorter, the voltage boosting signal Si is outputted with a greater duty ratio. The electric power supply 110 boosts the driving voltage, supplied from the external power source, to the set voltage value Vi by the regulator circuit. The phrase that "the electric power supply 110 is subjected to the voltage boosting", or that "the electric power supply 110 is boosted", or "to boost the driving voltage of the electric power supply 110" indicates, for example, in such a situation that an electric charge corresponding to the set voltage value Vi is accumulated in a power storage element such as the non-illustrated condenser, etc.

With this, the driving voltage of the electric power supply 110 is boosted gradually, as depicted in FIG. 12. Further, the controller 130 stands by to execute the processing including and after the step S54, until a stand-by time Ti (=25 msec) corresponding to the variable i elapses (S53: NO) since the execution of the processing of step S52 (namely, the output of the boosting signal Si). Then, in response to elapse of the stand-by time Ti since the output of the boosting signal Si (S53: YES), the controller 130 obtains the present value of the driving voltage retained by the electric power supply 110 just for a number of sampling count Ni (=four times) corresponding to the variable i , at a sampling interval li (=10 msec) corresponding to the variable i (S54). The processing of step S54 is an example of an obtaining processing.

More specifically, the controller 130 executes an A/D conversion to convert the present value of the driving voltage of the electric power supply 110 from an analogue value to a digital value, and causes the RAM 133 to temporarily store, as a first voltage value, the digitally converted present value. Next, in response to that the RAM 133 is caused to temporarily store the first voltage value, the controller 130 stands by until the sampling interval li elapses. Next, in response to the elapse of the sampling interval li , the controller 130 obtains a second voltage value. A method for obtaining the second voltage value is similar to the method for obtaining the first voltage value. Further, the controller 130 repeats these processings, until the con-

troller 130 obtains a N th voltage value. With this, N pieces of the voltage value are obtained.

Next, the controller 130 excludes the maximum voltage value and the minimum voltage value from the N pieces of the voltage value that the controller 130 has caused the RAM to temporarily store therein. Then, the controller 130 calculates an average value of the remaining ($N-2$) pieces of the voltage value (hereinafter referred to as an "average voltage value") (S55). The average voltage value is an example of a representative value of the N pieces of the voltage value. However, the specific example of the representative value is not limited to or restricted by this; it is allowable, for example, that the representative value is an average value of the N pieces of the voltage value, or may be the median of the N pieces of the voltage value.

Next, the controller 130 determines whether or not the average voltage value calculated in step S55 is not less than a threshold value Thi (=13.5 V) corresponding to the variable i (S56). The processing in step S56 is an example of a determining processing. Next, in response to the determination made by the controller 130 that the average voltage value is not less than the threshold value Thi (S56: YES), the controller 130 determines whether or not the driving voltage of the electric power supply 110 has reached the target voltage value (namely, whether or not the set voltage value Vi =the target voltage value) (S57).

In response to the determination made by the controller 130 that the driving voltage of the electric power supply 110 has not reached the target voltage value (S57: NO), the controller 130 increments the variable i by 1 (one) (S58), and executes the processings of steps S52 to S57 again. Alternatively, in response to the determination made by the controller 130 that the driving voltage of the electric power supply 110 has reached the target voltage value (S57: YES), the controller 130 completes the voltage boosting processing. Namely, until the driving voltage of the electric power supply 110 has reached the target voltage value (S57: NO), the controller 130 repeatedly executes the voltage boosting step, while gradually increasing (raising) the set voltage value V and the threshold value Th .

Further, in response to the determination made by the controller 130, during the execution of the voltage boosting processing in accordance with the second voltage boosting table, that the average voltage value is less than the threshold value Thi (S56: NO), the controller 130 reads out the first voltage boosting table depicted in FIG. 7A from the EEPROM 134 (S59). Then, the controller 130 executes the voltage boosting steps in accordance with the first voltage boosting table which has been read (S52 to S57). Namely, for example, in response to the determination made by the controller 130, during the second voltage boosting step ($i=2$) in accordance with the second voltage boosting table, that the average voltage value is less than a threshold value $Th2$ (S56: NO), the controller 130 may execute the second voltage boosting step in accordance with the first voltage boosting table, and the third voltage boosting step in accordance with the first voltage boosting table in this order. The voltage boosting processing in accordance with the third voltage boosting table is similar to those described above. On the other hand, in response to the determination made by the controller 130, during a certain voltage boosting step in accordance with the first voltage boosting table, that the average voltage value is less than the threshold value Thi (S56: NO), the controller 130 may execute again the processings of steps S52 to S57, without incrementing the variable i .

In the embodiment as described above, when comparing the first voltage boosting table, the second voltage boosting table and the third voltage boosting table depicted in FIGS. 7A, 7B and 7C, respectively, there is, for example, the following difference. As an example of the difference, the stand-by time T of the second voltage boosting table is shorter than that of the first voltage boosting table. As another example, the number of sampling count N of the i-th voltage boosting step in the second voltage boosting table is smaller than that in the first voltage boosting table. As yet another example, the sampling interval I of an i-th voltage boosting step in the third voltage boosting table is shorter than that in the second voltage boosting table. As still another example, the threshold value Th of the i-th voltage boosting step in the third voltage boosting table is smaller than that in the second voltage boosting table.

Note that the item(s) which is made to be different between the first and second voltage boosting tables is not limited to or restricted by the above-described example(s). Namely, it is allowable that at least one of the stand-by time T, the sampling interval I, the number of sampling count N and the threshold value Th is different between the first and second voltage boosting tables. This is similarly applicable also between the second and third voltage boosting tables. Although omitted in the drawings, the number of records in the second voltage boosting table (namely, the number of the voltage boosting step in the second voltage boosting pattern) may be made smaller than the number of records in the first voltage boosting table (namely, the number of the voltage boosting step in the first voltage boosting pattern). Similarly, the number of records in the third voltage boosting table (namely, the number of the voltage boosting step in the third voltage boosting pattern) may be made smaller than the number of records in the second voltage boosting table (namely, the number of the voltage boosting step in the second voltage boosting pattern).

Namely, as depicted in FIG. 10, the execution time of the voltage boosting processing in accordance with the second voltage boosting pattern becomes shorter than the execution time of the voltage boosting processing in accordance with the first voltage boosting pattern. Similarly, the execution time of the voltage boosting processing in accordance with the third voltage boosting pattern becomes shorter than the execution time of the voltage boosting processing in accordance with the second voltage boosting pattern. Further, as depicted in FIG. 10, the execution time of the FLS processing in which the CR velocity is 4 ips (second pattern) becomes longer than the execution time of the FLS processing in which the CR velocity is 60 ips (first pattern). Similarly, the execution time of the FLS processing in which the FLS execution count is three times (third pattern) becomes longer than the execution time of the FLS processing in which the FLS execution count is one time (second pattern).

Here, the FPOT is affected by whichever is longer among a time from the start of the voltage boosting processing and until the second moving processing is completed and a time from the start of the drive switching processing and until the completion of the initial setting processing. In view of time, as depicted in FIG. 10, provided that the time from the start of the drive switching processing and until the completion of the initial setting processing is a fixed value, the execution time of the voltage boosting processing is made to be shorter as the execution time of the FLS processing becomes longer (namely, the FLS shot count becomes greater, the elapsed time T becomes longer). As a result, the difference in the completion time (finish time) among the plurality of pro-

cessings which are executed in series becomes small, thereby making it possible to suppress the increase in the FPOT.

Note that the second voltage boosting pattern is not such a pattern by which the driving voltage is boosted rapidly to such an extent that any large load is applied to an electronic circuit configured to boost the voltage of the electric power supply 110. If, however, the voltage boosting processing in accordance with the second voltage boosting pattern is repeatedly executed, any small or slight load is consequently accumulated in the electronic circuit. In view of this, in a case that the execution time of the FLS processing is short, the first voltage boosting pattern in which the driving voltage is boosted in the relatively long voltage boosting time is used, thereby making it possible to reduce the load which would have otherwise accumulated in the electronic circuit. This is similarly applicable to the third voltage boosting pattern, as well.

Further, according to the above-described embodiment, in the preparing processing of the third voltage boosting pattern, the third voltage boosting step of the voltage boosting processing and the FLS processing are executed in parallel. With this, it is possible to further shorten the time from the start of the voltage boosting processing and until the completion of the second moving processing. As a result, in a case that the ink amount of the ink to be jetted in the FLS processing is large, it is possible to suppress the increase in the FPOT. Note that since the driving voltage at the time of the execution of the last voltage boosting step (22V) has been already boosted to have a value which is close to the target voltage value (24V), it is possible to jet the ink by a necessary ink amount, even executing the FLS processing without waiting the end of the voltage boosting processing.

<Modification>

In the above-described embodiment, the explanation has been made regarding the example in which the steps S41 to S47 are executed in response to the receipt of the image recording instruction. However, the execution timing at which the processings of the steps S41 to S47 are executed is not limited to or restricted by the above-described example. For example, the image recording instruction transmitted from the information processing apparatus 51 may include a preceding command and a recording command. The preceding command is a command previously announcing transmittance of the recording command. The recording command is a command for instructing the execution of the recording processing.

At first, in response to receipt, from a user, an instruction for causing the multi-function peripheral 10 to execute the image recording processing, the information processing apparatus 51 transmits the preceding command to the multi-function peripheral 10. Next, in response to that the information processing apparatus 51 has transmitted the preceding command, the information processing apparatus 51 generates a raster data from an image data designated by the user. Then, the information processing apparatus 51 transmits a recording command which includes the generated raster data to the multi-function peripheral 10.

On the other hand, the controller 130 of the multi-function peripheral 10 executes the processings of steps S41 to S43, in response to the receipt of the preceding command from the information processing apparatus 51 via the communicating section 50. Further, the controller 130 executes the processings of steps S44 to S47, in response to the receipt of the recording command from the information processing apparatus 51 via the communicating section 50 and in response to the completion of the processings of steps S41

to S43. According to the above-described configuration, it is possible to further shorten the FPOT. Furthermore, the preparing processing in accordance with the second pattern or the third pattern achieves a particularly advantageous effect in a case that the time of receiving the recording command before the voltage boosting processing is completed is short (namely, the time required for generating the raster data is short).

Further, the method for leveling the time from the start of the voltage boosting processing and until the completion of the second moving processing and the time from the start of the drive switching processing and until the completion of the initial setting processing is not limited to or restricted by the above described method. As another example, in a case that the execution time of the FLS processing is short (namely, the FLS shot count is less than the first ink amount) as depicted in FIG. 13A, the jiggling may be executed three times in the drive switching processing. On the other hand, in a case that the execution time of the FLS processing is long (namely, the FLS shot count is not less than the first ink amount) as depicted in FIG. 13B, the jiggling may be executed five times in the drive switching processing.

In the above-described modification, provided that the time from the start of the voltage boosting processing and until the completion of the second moving processing is a fixed value, the execution time of the drive switching processing is made shorter as the execution time of the flushing processing becomes shorter. As a result, the difference in the completion time among the plurality of processings which are executed in series becomes small, thereby making it possible to suppress the increase in the FPOT. The "five times" are an example of a first number of times, and the "three times" are an example of a second number of times.

Note that the driving gear 172 is smoothly separated away from the gear 176 by the jiggling executed three times, smoothly climbs (passes) over the gear 175, and is smoothly meshed with the gear 174. However, in a case that such an attempt is made that the switching of the meshing state of the gear 172 with respect to the gears 174 to 176 is performed with a small number of times of the jiggling, any small or slight load is consequently accumulated in each of the gears 172 to 177. In view of this, in a case that the execution time of the recording processing is long, even the shortening of the execution time of the drive switching processing does not contribute to the shortening of the FPOT. Therefore, by performing the jiggling five times, it is possible to reduce the load accumulated in each of the gears 172 to 177.

Furthermore, in the above-described embodiment, the explanation has been made regarding the example wherein the feeding rollers 25A and 25B, the ascending/descending mechanism for the cap 71, the conveyance roller 60, the discharge roller 62, and the pump 73 are driven by using the feeding motor 101 and the conveyance motor 102. It is allowable, however, that the feeding motor 101 is omitted and that the feeding rollers 25A and 25B, the ascending/descending mechanism for the cap 71, the conveyance roller 60, the discharge roller 62, and the pump 73 are driven by using the conveyance motor 102.

Moreover, in the above-described embodiment, the explanation has been made regarding the case wherein the recording head 39 is caused to jet the ink droplets in the process in which the carriage 23 is being moved in the main scanning direction. However, the recording head of the present teaching is not limited to or restricted by this; it is allowable, for example, that the recording head of the

present teaching may be a so-called line head in which the nozzles are arranged over the entire area of the sheet facing area.

Further, in the above-described embodiment, the explanation has been made regarding the case wherein the driving gears 172 and 173 are slid (slidably moved) in the direction of the supporting shaft, to thereby cause the driving gears 172 and 173 to make contact with and to be separated away from the gears 174 to 177. However, the configuration for causing the driving gears 172 and 173 to make contact with and to be separated away from the gears 174 to 177 is not limited to or restricted by the above-described example. As another example, each of the driving gears 172 and 173 may be a so-called pendulum gear. Namely, the driving gears 172 and 173 may swingably move or rockably move in a direction perpendicular to the supporting shaft to thereby mesh with the gears 174 to 177 or to be released from the meshing with the gears 174 to 177.

What is claimed is:

1. An ink-jet printer comprising:
a motor;
a conveyor configured to convey a medium;
a switching mechanism configured to switch between a transmitting state in which the switching mechanism transmits driving force of the motor to the conveyor and a non-transmitting state in which the switching mechanism does not transmit the driving force to the conveyor;
a recording head having a plurality of nozzles and a plurality of driving elements corresponding to the plurality of nozzles, respectively;
a power supply configured to output a driving voltage to be applied to the plurality of driving elements;
an ink receiver; and
a controller,

wherein in a case that the controller obtains an image recording instruction for instructing execution of recording of an image on the medium, the controller is configured to perform:

controlling the power supply to boost the driving voltage of the power supply to a target voltage value, and controlling the recording head to perform flushing by applying the driving voltage to all of the plurality of driving elements with a timing being determined such that the ink jettet from each of the plurality of nozzles lands on the ink receiver, in parallel with,
controlling the switching mechanism to switch the switching mechanism from the non-transmitting state toward the transmitting state, and

controlling the conveyor to perform conveyance of the medium up to an initial position where an area of the medium, in which the image is to be recorded first is capable of facing the recording head;

after completion of the flushing and the conveyance of the medium up to the initial position, applying the driving voltage, which has been boosted to the target voltage value, selectively to the plurality of driving elements, in accordance with the image recording instruction, to perform the recording of the image on the medium;
performing determination of an ink amount by which the recording head is configured to jet the ink in the flushing;

in a case that the determined ink amount is less than a first ink amount, controlling the power supply to boost the driving voltage of the power supply to the target voltage value, in accordance with a first voltage boosting pattern; and

31

in a case that the determined ink amount is not less than the first ink amount, controlling the power supply to boost the driving voltage to the target voltage value, in accordance with a second voltage boosting pattern in which a voltage boosting time is shorter than that in the first voltage boosting pattern, the voltage boosting time being a time period from starting boosting the driving voltage to reaching the target voltage value.

2. The ink-jet printer according to claim 1, wherein the controller is configured to repeat three processings for M times, the three processings including:

instructing the power supply to boost the driving voltage to a set voltage value V;
after elapse of a stand-by time T since the instructing, obtaining a value of the driving voltage outputted by the power supply for N times at a sampling interval I to obtain N pieces of values of the driving voltage; and determining whether or not a representative value of the obtained N pieces of values is not less than a threshold value Th being lower than the set voltage value V, wherein in a case that the controller determines that the representative value is not less than the threshold value Th, the controller is configured to raise the set voltage value V and the threshold value Th, and to repeat instructing the power supply to boost the driving voltage to the set voltage value V again, and wherein in the second voltage boosting pattern, a number of the N times by which the N pieces of values of the driving voltage is obtained is smaller than that in the first voltage boosting pattern.

3. The ink-jet printer according to claim 2, wherein in a case that the determined ink amount is not less than a second ink amount being greater than the first ink amount, the controller is configured to perform, in parallel with the flushing, the three processings repeated for M-th time.

4. The ink-jet printer according to claim 1, wherein the controller is configured to repeat three processings for M times, the three processings including:

instructing the power supply to boost the driving voltage to a set voltage value V;
after elapse of a stand-by time T since the instructing, obtaining a value of the driving voltage output by the power supply for N times at a sampling interval I to obtain N pieces of values of the driving voltage; and determining whether or not a representative value of the obtained N pieces of values is not less than a threshold value Th which is lower than the set voltage value V, wherein in a case that the controller determines that the representative value is not less than the threshold value Th, the controller is configured to raise the set voltage value V and the threshold value Th, and to repeat instructing the power supply to boost the driving voltage to the set voltage value V again, and wherein in the second voltage boosting pattern, the sampling interval I is shorter than that in the first voltage boosting pattern.

5. The ink jet printer according to claim 4, wherein in a case that the determined ink amount is not less than a second ink amount being greater than the first ink amount, the controller is configured to perform, in parallel with the flushing, the three processings repeated for M-th time.

6. The ink-jet printer according to claim 1, wherein the controller is configured to repeat three processings for M times, the three processings including:

instructing the power supply to boost the driving voltage to a set voltage value V;

32

after elapse of a stand-by time T since the instructing, obtaining a value of the driving voltage output by the power supply for N times at a sampling interval I to obtain N pieces of values of the driving voltage; and determining whether or not a representative value of the obtained N pieces of values is not less than a threshold value Th being lower than the set voltage value V, wherein in a case that the controller determines that the representative value is not less than the threshold value Th, the controller is configured to raise the set voltage value V and the threshold value Th, and to repeat instructing the power supply to boost the driving voltage to the set voltage value V again, and

wherein in the second voltage boosting pattern, the stand-by time T is shorter than that in the first voltage boosting pattern.

7. The ink-jet printer according to claim 6, wherein in a case that the determined ink amount is not less than a second ink amount being greater than the first ink amount, the controller is configured to perform, in parallel with the flushing, the three processings repeated for M-th time.

8. The ink-jet printer according to claim 1, wherein the controller is configured to repeat three processings for M times, the three processings including:

instructing the power supply to boost the driving voltage to a set voltage value V;
after elapse of a stand-by time T since the instructing, obtaining a value of the driving voltage output by the power supply for N times at a sampling interval I to obtain N pieces of values of the driving voltage; and determining whether or not a representative value of the obtained N pieces of values is not less than a threshold value Th which is lower than the set voltage value V, wherein in a case that the controller determines that the representative value is not less than the threshold value Th, the controller is configured to raise the set voltage value V and the threshold value Th, and to repeat instructing the power supply to boost the driving voltage to the set voltage value V again, and wherein in the second voltage boosting pattern, the threshold value Th is smaller than that in the first voltage boosting pattern.

9. The ink-jet printer according to claim 8, wherein in a case that the determined ink amount is not less than a second ink amount being greater than the first ink amount, the controller is configured to perform, in parallel with the flushing, the three processings repeated for M-th time.

10. The ink-jet printer according to claim 1, wherein the controller is configured to repeat three processings for M times, the three processings including:

instructing the power supply to boost the driving voltage to a set voltage value V;
after elapse of a stand-by time T since the instructing, obtaining a value of the driving voltage output by the power supply for N times at a sampling interval I to obtain N pieces of values of the driving voltage; and determining whether or not a representative value of the obtained N pieces of values is not less than a threshold value Th which is lower than the set voltage value V, wherein in a case that the controller determines that the representative value is not less than the threshold value Th, the controller is configured to raise the set voltage value V and the threshold value Th, and to repeat instructing the power supply to boost the driving voltage to the set voltage value V again, and

33

wherein in the second voltage boosting pattern, a number of the M times for which the three processings are repeated is smaller than that in the first voltage boosting pattern.

11. The ink-jet printer according to claim 10, wherein in a case that the determined ink amount is not less than a second ink amount being greater than the first ink amount, the controller is configured to perform, in parallel with the flushing, the three processings repeated for M-th time. 5

12. The ink jet printer according to claim 1, wherein in a case that the determined ink amount is not less than a second ink amount being greater than the first ink amount, the controller is configured to control the power supply to boost the driving voltage of the power supply to the target voltage value, in accordance with a third voltage boosting pattern in which a voltage boosting time is shorter than that in the second voltage boosting pattern. 10 15

13. The ink-jet printer according to claim 1, further comprising:

a medium sensor configured to detect the medium conveyed by the conveyor; and

34

a carriage on which the recording head and the medium sensor are mounted, the carriage being configured to move in a scanning direction, crossing a conveyance direction in which the medium is conveyed by the conveyor, in an area including a medium facing area where the carriage faces the medium conveyed by the conveyor,

wherein the ink receiver is arranged at a position separated from the medium facing area in the scanning direction;

the controller is configured to perform:

causing the carriage to move to the medium facing area, after completion of the flushing, and

the recording of the image on the medium, after the medium is detected by the medium sensor in a process during which the medium is being conveyed up to the initial position and after completion of the conveyance of the medium up to the initial position.
